JOHN B. LUKOMSKI, OF DETROIT, MICHIGAN

CORE BOX

Application filed November 5, 1928. Serial No. 317,196.

The present invention pertains to a novel core box for making the cores to be used in casting tubular fittings. Such a core box is a substantially cylindrical body with closed ends, and the end closures are usually integral with the body. Due to the fact that the ends are closed, there is considerable difficulty in reaching the inner surfaces for the core box for finishing or machining the same, and the finishing operation is performed to a great extent by means of hand tools.

The object of the present invention is to construct and assemble the core box in such a manner that the inner surface of the body at least may be finished by a mechanically operated tool. With this object in view, the body is constructed as an open-ended member so that a reamer or other suitable power driven tool may be inserted through one end and thus utilized to finish the interior surface. The sections of the box are now laid on a board, and a mold is built over the ends thereof for the formation of the end portions by pouring metal therein. Preferably joining members are previously inserted in the ends of the open-ended body and become anchored in the metal which is cast over the ends.

The invention is fully disclosed by way of example in the following description and in the accompanying drawing, in which—

Figure 1 is a plan view of the core box in open condition;

Fig. 2 is a longitudinal section of the core box in closed condition, showing in elevation an arbor therein;

Fig. 3 is an end view of the closed core box;

Fig. 4 is a section on the line 4—4 of Fig. 2;

Fig. 5 is a plan view of one of the body sections;

Fig. 6 is an end view thereof; and

Fig. 7 is a longitudinal section showing the construction of the mold for casting the end closures on the ends of the body sections.

Reference to these views will now be made by use of like characters which are employed to designate corresponding parts throughout.

The core box illustrated in the drawings

is designed to form a core for a straight fitting or pipe section. The body of the core box is therefore straight and substantially cylindrical and has end caps or closures so that there will be formed a core box in the nature of an enclosed receptacle as usual. Ordinarily the end caps are integral with the body sections, but in the present invention a departure is made by providing the core box halves in the nature of tubular members 1 with open ends 2. Due to the fact that the ends are open, the sections may be clamped together in a suitable jig and finished internally by a reamer or other suitable power driven tool inserted through the ends. This means of finishing the interior of the body is a considerable saving over the means which would be resorted to if the ends were closed in the customary manner.

After being machined in the manner described, each of the sections 1 is filled with a half core 3 of the size which would be made thereby in the finished core box. The half core and section are laid on a board 4, and sand molds 5 are built around the ends thereof so that the cavity 6 contains the core ends and also the ends of the section 1. Previous to forming the molds, joining members such as screws 7 are preferably driven partly into the ends of the section 1, so that when metal is poured into the molds, it will have the members partly embedded therein. The shape of the molds is such as to form the requisite end caps or closures, which, as already indicated, will be positively united to the ends of the section 1 by means of the members 7. Figure 7 illustrates one of the sections 1 set up for the formation of caps at both ends thereof. The remaining section need have only one cap cast thereon, and the uncovered end will be closed by the means presently to be described.

After the sections 1 have been capped, they are connected by means of hinges 8 and are fastened to the hinges by screws 9 which enter thickened portions 10 of the sections. The sections are located on the hinges in such a manner that when the latter are closed, the sections will fit accurately one over the other.

Prior to filling the sections with sand for

the formation of a core, an arbor 11 is laid in the section which has a cap at only one end. A finger piece or tab 12 of the arbor extends through the open end, while adjacent to the tab is formed a semi-circular disk 13 which closes this end. The outer surface 14 of the disk is conical and is the counterpart of the surface which will be formed on the core by the immediately adjacent cap 15 of the other section 1, as clearly illustrated in Figure 2. Thus, the disk 13 constitutes a half of one of the ends of the completed core.

Although a specific embodiment of the invention has been illustrated and described, it will be understood that various alterations in the details of construction may be made without departing from the scope of the appended claim.

20 What I claim is:—

A core box comprising a pair of core sections, one of said sections having an open end, a cap at the other end of said section, an arbor receivable within the first named section, and a disk formed on said arbor and adapted to close the open end of said section.

In testimony whereof I affix my signature.

JOHN B. LUKOMSKI.
